AUTOMATIC TELEPHONE SIGNALING
APPARATUS

Jean Edouard Tuscher, Petit Ivry, and Marcel Spiro, Paris, France, assignors to Societe de L'Aviseur Telephonique Automatique, Paris, France, a corporation of France

Application December 5, 1932, Serial No. 645,846
In France December 9, 1931

16 Claims. (Cl. 179—5)

This invention relates to protective alarm systems for buildings, adapted automatically to transmit an alarm message telephonically, and more especially to systems of this character capable of operating in conjunction with a subscriber's telephone line terminating at an automatic exchange.

An object of the invention is the provision of a protective system for association with a dial actuated subscriber's telephone line which, upon occurrence of conditions requiring that an alarm be given, will automatically dial a preselected station and transmit an alarm message phonographically thereto.

A feature of the invention is the optional incorporation therein of means whereby the alarm apparatus will dial in sequence two or more preselected stations and transmit the alarm message phonographically to each. This same modification permits of calling stations several times in succession to guard against the contingency of a busy line.

The apparatus whereby these results are achieved is reliable of operation and of compact structure. The employment therein of a microphone pick-up for translating the stylus vibrations directly into electrical oscillations, assures such silent operation in giving the alarm as not to warn an intruder. To further this end the alarm mechanism which is separate and apart from the subscriber's telephone set, may be housed in a sound-proof casing, and placed out of sight, as for example, in a desk drawer, etc.

In the drawings:

Fig. 1 is a composite showing of the electrical protective circuits and cooperating mechanical features illustrating the principles of operation for a modification of the invention actuated from an electrically driven motor.

Fig. 2 is a sectional elevation of the dialling mechanism incorporated in the Fig. 1 structure.

Fig. 3 is a wiring diagram showing the manner in which the dialling mechanism and phonographic message transmitting device of the protective system are associated with a subscriber's telephone line extending to an automatic exchange.

Figs. 4-13 inc. show a second modification of the invention actuated by a mechanically driven motor.

Figs. 4 and 5 show in plan view and sectional elevation the mechanical details of this construction.

Fig. 6 is a wiring diagram of the telephone connections.

Fig. 7 is a detail showing the mechanical features of the starting device.

Figs. 8 and 8a are details illustrating the mechanism for stopping the device.

Figs. 9 and 10 are respectively an elevation 60 and a sectional elevation of the cam actuated dialling mechanism.

Fig. 11 illustrates an individual dialling cam, and Fig. 12 an annular blank insert for separating the dialling cams. 65

Figs. 13 and 14 are respectively a circuit diagram of the telephone connections, and a longitudinal elevation partly in section showing the mechanical features of a modified construction 70 of the dialling mechanism whereby alarm messages may be sent to several stations successively.

Figs. 15, 16a and b, 17a and b, and 18a and b, show in plan view and elevation, the components of the cam assembly incorporated in the Fig. 14 75 construction, for breaking the microphone circuit between successive calls, and for actuating the dialling mechanism at proper intervals in the desired sequence. Fig. 15 shows the collar upon which are assembled the cams Figs. 16 and 18 separated by insert blanks Fig. 17.

Figs. 19a and b show in plan view and sectional elevation, a frusto-conical insert member of the repeat call dialling mechanism of the Fig. 14 80 assembly.

In the embodiment of the apparatus illustrated in Figs. 1 to 3, the protective circuit 101 is normally closed by a plurality of switches 102 located at various points on the premises to be protected and which will be opened in the usual way when 90 such premises are invaded. The protective circuit 101, energized from a source of electrical power supplied to terminals 100, and controlled by a switch 103 having an off position 104, normally energizes an electromagnet 105 to open a

switch 106 closure of which completes a circuit over conductor 107 through an electromagnet 108 which, when energized, starts the signaling apparatus in a manner presently to be described. Alternatively energization of electromagnet 108 95 may be under control of normally open protective circuits such as those including switches 109 and 109', adapted to be closed upon entry of an intruder.

The electromagnet 108 when energized, attracts a lever 110 which starts the motor 111 of the signaling apparatus. The motor, in turn, through the medium of the speed reducer 112, rotates the driving spindle 113 of the dialling mechanism, and the spindle 114 of a support for 110

the phonographic record, cylinder or strip on which is recorded a suitable message of warning to the station dialed that the protected premises are being invaded.

5 The spindle 115 of the dialling device is axially displaceable. To permit this, its upper end is splined in a quill portion of the spindle 113 of the speed reducer and is driven by said spindle 113 through the medium of a pin 116 mounted 10 in an axial slot of the spindle 113. The lower end 117 of the spindle 115 is threaded and screws in a socket 118 fixed to the frame of the apparatus. The movement of the spindle of the dialling device is therefore the combination of 15 a rotational one imparted by the spindle 113 of the speed reducer, and a vertical translational movement controlled by the threaded socket 118.

When the spindle 115 has reached the position illustrated in Fig. 2, its driving finger 116 clears 20 the spindle 113 so that movement of said spindle 115 then ceases. To return the dialling device to its initial position, it is only necessary to screw the socket 118 until spindle 115 is returned to its position shown in Fig. 1. The spindle 115 25 of the dialling device carries one or more dialling cams 119 and a drum 120 to which are imparted its combined rotational and translational movement.

In Fig. 3, wiring diagram showing the telephone 30 connections, 121 represents the conventional wiring of a subscriber's telephone station arranged for dialling. The subscriber's station is connected over conductors K to an automatic telephone exchange.

35 The alarm system is connected at a convenient point to the subscriber's line k over conductors 122, included in a circuit traced seriatum through contacts of a normally open switch 123, normally closed contacts of switch 126b, controlled by the 40 aforementioned drum 120, and normally closed contacts of switch 126b, actuated by the dialling cam 119, whereby dialling impulses may be transmitted to line k from the alarm system. Closure of switch 123 is effected during rotation of motor 45 111, through lateral displacement of the slide-block 124 affixed to the centrifugal governor 125, thus connecting the alarm apparatus to line k .

During the dialling operation the contacts of 50 switch 126a are maintained closed by drum 120 in the manner shown in Fig. 1, thereby to short circuit the microphone pick-up 127 of the phonograph mechanism as shown in Fig. 3. Upon completion of the dialling, however, the axial advance of drum 120 opens switch 126a in the manner 55 of Fig. 2, to connect the microphone pick-up 127 in the circuit traced over conductors 122 in order that the alarm message may be transmitted to line k and thence to the station dialed.

Automatic operation of the system to dial a 60 selected station and transmit the alarm message thereto are effected as follows: The alarm mechanism having been set by closure of switch 104, entry of the protected premises opens a switch 102, or closes a switch 109, to energize relay 108 65 in the manner described. The motor 111 having been started by actuation of lever 110 upon energization of electromagnet 108, the axial displacement of the slide block 124 due to rotation of the centrifugal governor 125, closes switch 123 70 to complete the circuit traced from line k through the dialling switch 126b. Current from the central office then flows from one side of line k through switches 126a and 126b, both of which are closed, and returns to the other side of line 75 k , the microphone pick-up 127 being thus short-

circuited. As the teeth of cams 119 in their combined rotational and translational movement pass successively under the push button of switch 126b, the telephone circuit is opened a predetermined number of times and in a dialling sequence adapted to establish connection with the station to be called. The dialling impulses are controlled by the number, shape and location of the teeth on each cam, the number of cams, the speed of rotational and translational movement, etc.

If the telephone is of the automatic exchange type, the cams 119 and the drum 120 are designed in such manner as to call the required number, i. e. to reproduce automatically the dialling operations of the manual dialling device of the subscriber's telephone set 121. If, however, the telephone is of the manual exchange central office battery type, the dialling cams are not required for the reason the direct current path established between the conductors of line k upon closure of switch 123, will light the pilot lamp before the central office operator, and she will answer in the usual way to complete the call to the desired station in accordance with instructions transmitted phonographically from the microphone pick-up 127.

In the modification illustrated in Figs. 4 to 13 inclusive, the motor of the apparatus is a mechanical motor whose spring is lodged in the drum 1. The spring re-winding mechanism is shown at 2. The whole apparatus is mounted within a casing 3 which may incorporate a sound proofing material. The crown wheel 4 of the drum drives the various mechanisms of the apparatus through a gear train 5—6, 7—8, 9 and 10. The spindles of the drum and gears are mounted between two mounting plates 11 and 12 which are braced by three struts 13 resiliently mounted on the casing 3 of the apparatus.

The signaling apparatus operates as follows: When one of the contacts 102 and 109 of the protective circuit illustrated in Fig. 1 is actuated, the electro-magnet 14, Figs. 4, 5 and 7, is energized and attracts its armature 15 which, through the medium of the pivot lever 16, releases the drop 17, the latter as it falls, depressing the rod 18 below the stop pin 20 fixed on the ledge of the turntable 19 of the phonograph, thus initiating operation of the entire mechanism. The turntable 19 set on the spindle of the pinions 7 and 8 being released, the spring of the drum 1 unwinds driving the various members of the apparatus through the rotation of the crown wheel 4 and of the pinions 5—6, 7—8, 9 and 10.

The telephone connection, Fig. 6, is made for example at any suitable point of the telephone line k extending from the subscriber's set 21 to an automatic exchange. When the driving motor of the protective apparatus is stationary, the circuit of the subscriber's telephone is by way of k , b , c , I , that is, through the contacts b — c of the two-way switch b c d of the signalling apparatus. The two-way switch b c d is controlled automatically by the slide block h of a centrifugal governor 21.

When the motor of the apparatus is started up by the means previously described, the slide block h of the governor rises and lifts the push button 22 of the contact blade b . The first circuit k b c l to the subscriber's telephone is then broken while the slide block h , continuing on its upstroke, establishes contact between the two upper blades b d of the telephone line k extending from the central office being then closed by way of k b d .

e f g h, that is through a second two-way switch *e f g*, controlled by an automatic dialling device *n* having a helicoidal motion.

The dialling device *n* illustrated in Figs. 9 and 10, is at this instant in the position of Fig. 9 in which it holds the switch *e f g* closed by acting on the push button 23. When, after several seconds' rotation of the dialling device *n*, the push button 23 of the switch encounters the sets of dialling cams 24, the contacts *f g* are broken as each cam tooth passes under the push button 23 at the required rate to actuate the selectors of the exchange, and consequently to call the number of the emergency station sought for.

15 During the dialling operation, however, contacts *e f* remain closed thereby short-circuiting the microphone pick-up *m* of the phonograph.

When the dialling operation is terminated (position shown in Fig. 10), the contacts *f g* of switch *e f g* remain closed, whereas the contacts *e f* are broken, thus establishing the microphone pick-up circuit *k b d r' m f g k*. To avoid arcing at the contacts *f g* during the operation the dissipative circuit, comprising condenser 10 in series with damping resistance *r*, is arranged in shunt thereto as shown.

30 The adjustable resistance *r'* is inserted in the circuit of the microphone pick-up *m* to adjust, according to the resistance of the line and the voltage of the exchange battery, the signal intensity reproduced at the called station.

As soon as the emergency signal has been emitted for a predetermined time, the motor is stopped by means presently to be described. The slide block *h* of the governor 21 then returns to its position of rest, first breaking the microphone circuit *k b d r' m f g k*, and then remaking the subscriber's telephone circuit *k b c l k*, whose line is released.

40 The spindle 25 of the dialling device *n*, Fig. 10, rotates at predetermined speed in a tapped guide member 26, mounted on the mounting plate 12. It is driven by the pinion 9 through the toothed wheel 6 and rotates in an adjustable step bearing 45. 27. The dialling device *n* is constituted by a cylindrical member to which a helicoidal movement is imparted through the medium of a pin 28 secured to the spindle 25, said pin sliding in a suitable slot of the dialling device *n*. The pitch of the helix is determined by the thread of the support 26 onto which the dialling device *n* is screwed in such wise that the push button 23 of the switch *e f g* is pushed back successively by each tooth of the cams 24. Said cams 24 are so cut out that 50 the digit 0, comprising a series of ten interruptions, occupies half the circumference of an individual cam, Fig. 11. In this manner, between each set of interruptions corresponding to the digits of the number called, there occurs between successive digits, a closure (minimum for the digit 55 0) of the circuit *k b d e f g k* (Fig. 6) corresponding to an interval of at least half a revolution of the dialling device *n*.

The dialling device *n* includes as many dialling cams 24 as there are digits in the number of the station called. Each cam is separated from the next one by an insert member 29, Fig. 12. The cams and their insert pieces are centered on the dialling device *n* and are clamped by a screw 30.

70 When, after dialling, the dialling device is arrested in the position of Fig. 10, the circuit *k b d r' m f g k* is established. The microphone of the phonograph pick-up *m* is of standard construction. It is mounted in a casing 31 by means of a screw 32 at the end of an arm 33, mounted to

swivel in all directions on a pivotal support 34 carried by the plate 12 as shown in section in Fig. 5.

A phonograph diaphragm stylus support is mounted on the casing 31. The sound vibrations transmitted by the emergency signal call recorded on the record 36 are transmitted to the carbon membrane 37 of the microphone *m* by the screw 38 of the support 35 which bears on the carbon membrane through the medium of a leaf 39 with a pressure that can be adjusted. The screw 38 passes through a resilient membrane 40 affixed to the bottom of the casing 31, which membrane attenuates stray vibrations in the telephonic transmission of the call recorded.

80 The call is recorded on the surface of the record 36 for a width corresponding to a revolution of the drum 1, that is to say, approximately 40 turns for the apparatus illustrated herein. When the needle has traversed these forty turns, a finger 41 fixed on a cursor 42 of the arm 33 encounters a cam 43 rotating with the drum 1. Said cam 43 is slotted so that in passing under the finger 41 it raises the microphone and rotates it until the needle 44 of the record returns to its starting position on the record 36. The call recorded is thus repeated at each revolution of the drum 1. By causing the cursor 42 to rotate and slide on the arm 33, the lift and angular displacement of the needle 44 of the microphone are adjusted. The knob 45 enables the cursor 42 to be clamped on its spindle.

95 To restrict the telephone signal to a predetermined time duration or number of signals, the drum 1 carries laterally one or more fingers 46 100 which drive a ratchet wheel 47 (Figs. 8 and 8a) mounted on a spindle 48 provided with a tapped head 50 which screws into a support 49 fixed under the upper plate 11. When the screw head 50, abuts the plate 11, the ratchet 47 arrests the driving finger 46 and hence the drum 1 and the whole apparatus. In this manner, untimely breaking of the telephone circuit through the switch *b c d* due to oscillations of the slide block *h* of the centrifugal governor when the motor spring no longer 105 supplies a sufficient torque, are avoided.

110 The rated speed of the whole apparatus is regulated through the medium of the lever 51 (Fig. 4) which limits the up stroke of the slide block *h* of the governor 21 through a stop 52 at the end of 115 the lever 51.

120 When the apparatus is arranged to warn the same emergency station or several different stations, several times in succession, the telephonic wiring diagram (Fig. 13) is the same as for a 125 single call, but with the addition of a switch *o p* included in the circuit of the microphone pick-up *m*, and controlled at predetermined intervals by one or more cams 54.

130 The mechanism allowing successive calls to be 135 made is illustrated by way of example, in Fig. 14, for three successive calls to emergency stations, whose telephone numbers each comprise two digits. The automatic dialling device *n*, Fig. 14, shown in sectional elevation, includes three sets 140 of two dialling cams 24 separated by the insert members 29. Each set of cams is separated by frusto-conical insert members 55, the larger base of each of which faces upwardly.

145 The pinion 9 driving the shaft 25 of the dialling device is mounted on a sleeve 56 freely rotatable in cylindrical bearings of the support 26 of the dialling device. The pinion 9 carries on its lower face one or more driving fingers 57, while the spindle of the dialling device has mounted on 150

an appropriated collar 58 another driving finger 59 in alignment with fingers 57.

The shaft 48 of the stopping mechanism is extended below the ratchet wheel 47 to receive the collar 60 whose angular position on the spindle is controlled by a needle screw. On the collar 60 are assembled the cams 54 controlling the switch *o p* (Fig. 13) and the cam 61 controlling the movement of the dialling device *n* through the medium of a clutch lever 62 pivoted on the spindle 63.

The repeat call signaling apparatus operates as follows: When the fall of the shutter 17 (Fig. 7) has set the apparatus in motion through the means previously described, the adjustable screw 64 of the lever 62 encounters the first cam 61 controlling the dialling device *n* after a time interval determined by the position of the driving fingers 46 of the ratchet 47 on the drum 1. At this moment, the end 65 of the lever 62 will raise the spindle 25 of the dialling device *n*, one of the driving fingers 57 of the pinion 9 will meet, as it rotates, the corresponding finger 59 of the clutch disc 58 of the spindle 25. The spindle 25 will then start rotating, driving, through the means previously described, the dialling device *n*, for a length of time determined by the length of the cam 61 and sufficient to assure dialing of the digits, two in the example illustrated, of the first station called.

As the teeth of dialling cams 24 pass successively under the push button 23 of switch *e f g* (Fig. 13), the switch is actuated in the same manner as previously described for the case of a single call. When the first telephone number has been called, the cam 61 releases the screw 64, while the spring 66 fixed on the upper plate 11 of the apparatus thrusts the spindle 28 downwardly into its position of rest. The dialling device will then be locked, the push button 23 on the switch *e f g* dropping into the groove provided by the first frusto-conical insert 55. This causes the switch contacts *g f* to remain closed and the contacts *f e* to be opened, thereby connecting the microphone pick-up *m* to line *k* for transmitting the alarm message to the first station called.

The ratchet wheel 47 continuing its intermittent helicoidal motion, will elevate with it the collar 60 until the screw 64, having traversed the first insert blank 67, encounters the first cam 54. When, in its movement, the cam 54 encounters the push button 53 of the switch *o p*, the telephone circuit is broken at *o p* and the first call will terminate. This first break of the circuit will last for a time corresponding to the length of the cam 54, then the telephone circuit will be established at *o p*. After a time interval determined by the thickness of the second insert piece 67 and the angular position of the collar 60, the second cam 61 will encounter the screw 64 causing the dialling device to be moved a second time in the manner described, to make the second call. The second conical insert member 55 will then open contacts *e f* to connect the pick-up *m* to line *k* for transmission of the alarm message to the second station. This sequence of operations will be repeated in the same manner for the third or any greater number of calls.

The duration of the last call is regulated by the screw 68, the end 69 of which will act as a stop for the advancing head 50 of the spindle 48, to prevent further rotation of the drum 1. Thereupon contacts *b d* of switch *b c d* will open to disconnect the alarm apparatus from line *k*.

which will then be reconnected to the subscriber's station 21 through switch contacts *b c*.

We claim:

1. In an alarm system in combination, an automatic exchange telephone line, a protective circuit, a motor, means responsive to a disturbance of said circuit for starting said motor, impulse transmitting means adapted to dial several stations responsive to said motor for automatically connecting said line to a particular station, a phonographic device actuated by said motor to send an alarm message over said line subsequent to said station selection, said device having a non-acoustical pick-up for silent actuation, means producing continuous repetition of said phonographic message so long as said motor is operative and means abruptly stopping the motor to terminate said alarm after a predetermined plurality of message repetitions. 80

15 2. In combination, an automatic exchange telephone line extending to a dial telephone set, an alarm system separate and distinct from said set comprising a protective circuit, a motor, means responsive to a disturbance of said circuit for starting said motor, and means operated by said motor consisting of, a switch centrifugally actuated to disconnect said set from said line and to connect said alarm system thereto, cam actuated multiple digit dialling means for automatically connecting said line to a particular station, a phonographic device actuated by said motor to send an alarm message over said line subsequent to dialing, means producing continuous repetition of said message while said motor is operative, and means stopping said motor after a predetermined number of message repetitions. 90

20 3. In combination, an automatic exchange telephone line extending to a dial telephone set, an alarm system separate and distinct from said set comprising a protective circuit, a motor, means responsive to a disturbance of said circuit for starting said motor, and means operated by said motor consisting of, a switch centrifugally actuated to disconnect said set from said line and to connect said alarm system thereto, cam actuated multiple digit dialling means for automatically connecting said line to a particular station, a phonographic device actuated by said motor to send an alarm message over said line subsequent to dialing, means producing continuous repetition of said message while said motor is operative, and means stopping said motor after a predetermined number of message repetitions. 100

25 4. In an alarm system in combination, an automatic exchange telephone line, a protective circuit, a motor, means responsive to disturbance of said circuit for starting said motor, and means operated by said motor comprising, cam actuated dialing means for connecting said line to a particular station, said means including a cam disc for each digit of the called station number, a phonographic device adapted to send an alarm message over said line, means connecting said device thereto subsequent to said station selection thereby to prevent transmission of false impulses during dialing, and means abruptly stopping said motor to terminate the alarm after a predetermined alarm interval. 115

30 5. In an alarm system in combination, an automatic exchange telephone line, a protective circuit, a motor, means responsive to disturbance of said circuit for starting said motor, and means operated by said motor comprising, cam means actuating impulsing means for connecting said line to a particular station, said cam means including a drum bearing a separate cam disc for each digit of the called number, means for imparting helicoidal motion to said drum whereby said discs operate successively on said impulsing means, a phonographic device adapted to send an alarm message, means operatively connecting said device to said line subsequent to the station selection, and means abruptly stopping said motor to terminate the alarm. 130

35 6. In an alarm system in combination, an automatic exchange telephone line, a protective circuit, a motor, means responsive to a disturbance of said circuit for starting said motor, impulse transmitting means responsive to said motor for automatically connecting said line in sequence to a plurality of prearranged stations, phonograph means actuated by said motor to send an 140

40 7. In an alarm system in combination, an automatic exchange telephone line, a protective circuit, a motor, means responsive to a disturbance of said circuit for starting said motor, impulse transmitting means responsive to said motor for automatically connecting said line in sequence to a plurality of prearranged stations, phonograph means actuated by said motor to send an 145

45 8. In an alarm system in combination, an automatic exchange telephone line, a protective circuit, a motor, means responsive to a disturbance of said circuit for starting said motor, impulse transmitting means responsive to said motor for automatically connecting said line in sequence to a plurality of prearranged stations, phonograph means actuated by said motor to send an 150

- alarm message to each said station, and means for automatically stopping said motor thereafter. 80
6. In an alarm system in combination, an automatic exchange telephone line, a protective circuit, a motor, means responsive to a disturbance of said circuit for starting said motor, impulse transmitting means responsive to said motor for automatically connecting said line in sequence to a plurality of prearranged stations, phonograph means actuated by said motor to send an alarm message to each said station, means for automatically stopping said motor thereafter, and means preventing said message transmission during selection of said stations thereby to prevent transmission of false dialing impulses. 85
7. In combination with an automatic exchange telephone line, an alarm system comprising, a protective circuit, a motor, means responsive to disturbance of said circuit for starting said motor, a phonographic device adapted to send an alarm message over said line, impulsive means adapted to connect said line in sequence to a plurality of stations, and clutch means responsive to said motor for causing said impulsive means to select a station and for thereafter connecting said phonographic device to said line thereby to transmit the alarm message, said clutch means being subsequently operative similarly to connect said line to each of the remaining stations. 90
8. In an alarm system in combination, an automatic exchange telephone line, a protective circuit, a motor, means responsive to disturbance of said circuit for starting said motor, a phonographic device adapted to send an alarm message over said line, impulsive means for automatically connecting said line in sequence to a plurality of stations, cam driven clutch means intermittently actuated by said motor for causing said impulsive means to select said stations, said clutch means releasing for an interval following each said selection to permit transmission of the alarm message, and means stopping said motor following transmission of the alarm to all stations. 95
9. In an alarm system in combination, an automatic exchange telephone line, a protective circuit, a motor, means responsive to a disturbance of said circuit for starting said motor, and means operated by said motor comprising, a phonographic device adapted to send an alarm message over said line, cam actuated impulsive means for automatically connecting said line in sequence to a plurality of stations, said cam means including a plurality of cam discs assembled in spaced relation on a spindle in sets corresponding to the stations to be called, and in number per set according to the digits of the called stations respectively, means for imparting helicoidal motion to said spindle whereby said cam discs act successively upon said impulsive means, and means for operatively associating said phonographic device with said line between successive stations selection for transmission of the alarm message to each. 100
10. In combination with a telephone line extending to a central office, an alarm system comprising, a protective circuit, a motor, means responsive to disturbance of said circuit for starting the motor, and means actuated thereby for signaling the central office and thereafter sending an alarm message over said line, and a rotatable member helicoidally advancing to abutment with a fixed member to stop said motor after a predetermined interval of rotation. 105
11. In combination with a line connecting a telephone set with a central office, an alarm system distinct from said set comprising, a protective circuit, a motor, means responsive to disturbance of said circuit for starting the motor, and means actuated thereby consisting of, a centrifugally actuated switch for disconnecting said set and connecting the alarm system to said line, means for signaling the central office and for thereafter sending an articulate alarm message over said line, and means abruptly stopping the motor after a predetermined interval of rotation to prevent transmission of false dialing impulses. 110
12. In combination with an automatic exchange telephone line, an alarm system comprising, a protective circuit, a motor means responsive to the disturbance of said circuit for starting the motor, a phonographic device operated thereby and having an electrical output path adapted to send an alarm message over said line impulsive means for automatically connecting said line to a particular station, said impulsive means being operative to short circuit said output path during station selection, thereby to prevent false dialing impulses and to thereafter remove said short circuit for transmission of the alarm message, and means automatically opening said output path following transmission of said message thereby to release said station and terminate the alarm. 115
13. In combination with an automatic exchange telephone line, an alarm system comprising, a protective circuit, a motor, means responsive to a disturbance of said circuit for starting the motor, a phonographic device operated thereby and having an electrical output path adapted to send an alarm message over said line, impulsive means for automatically connecting said line in sequence to a plurality of preselected stations, said impulsive means being operative with respect to each station, to short circuit said output path during station selection, thereby to prevent false dialing impulses and to thereafter remove said short circuit to permit transmission of the alarm message, and means automatically opening said output path following transmission of each said message thereby to release each station and permit selection of the succeeding station, and means abruptly stopping said motor following transmission of the alarm message to all said stations. 120
14. In an alarm system in combination, an automatic exchange telephone line, a protective circuit, a motor means responsive to electrical disturbance of said circuit for starting said motor, dialling means operated by said motor including a helicoidally advancing drum provided with spaced cam discs successively actuating impulsive means for automatically connecting said line to a particular station, a phonographic device for sending an alarm message over said line, and a switch actuated upon advance of said drum for operatively connecting said phonographic device to said line subsequent to dialling. 125
15. In an alarm system in combination, an automatic exchange telephone line, a protective circuit, a motor, means responsive to disturbance of said circuit for starting the motor, dialling means responsive thereto including an intermittently actuated helicoidally advancing drum provided with groups of spaced cam discs successively actuating impulsive means for automatically connecting said line in sequence to a plurality of stations, and a second switch actuated upon advance of said drum by frusto-conical inserts separating said cam groups for operatively connecting said phonographic device to said line for an alarm interval following each station selection. 130
16. In an alarm system in combination, an automatic exchange telephone line, a protective circuit, a motor, means responsive to disturbance of said circuit for starting the motor, dialling means responsive thereto including an intermittently actuated helicoidally advancing drum provided with groups of spaced cam discs successively actuating impulsive means for automatically connecting said line in sequence to a plurality of stations, and a second switch actuated upon advance of said drum by frusto-conical inserts separating said cam groups for operatively connecting said phonographic device to said line for an alarm interval following each station selection. 135
17. In an alarm system in combination, an automatic exchange telephone line, a protective circuit, a motor, means responsive to disturbance of said circuit for starting the motor, dialling means responsive thereto including an intermittently actuated helicoidally advancing drum provided with groups of spaced cam discs successively actuating impulsive means for automatically connecting said line in sequence to a plurality of stations, and a second switch actuated upon advance of said drum by frusto-conical inserts separating said cam groups for operatively connecting said phonographic device to said line for an alarm interval following each station selection. 140
18. In an alarm system in combination, an automatic exchange telephone line, a protective circuit, a motor, means responsive to disturbance of said circuit for starting the motor, dialling means responsive thereto including an intermittently actuated helicoidally advancing drum provided with groups of spaced cam discs successively actuating impulsive means for automatically connecting said line in sequence to a plurality of stations, and a second switch actuated upon advance of said drum by frusto-conical inserts separating said cam groups for operatively connecting said phonographic device to said line for an alarm interval following each station selection. 145
19. In an alarm system in combination, an automatic exchange telephone line, a protective circuit, a motor, means responsive to disturbance of said circuit for starting the motor, dialling means responsive thereto including an intermittently actuated helicoidally advancing drum provided with groups of spaced cam discs successively actuating impulsive means for automatically connecting said line in sequence to a plurality of stations, and a second switch actuated upon advance of said drum by frusto-conical inserts separating said cam groups for operatively connecting said phonographic device to said line for an alarm interval following each station selection. 150

16. In an alarm system in combination, an automatic exchange telephone line, a protective circuit, a motor, means responsive to disturbance of said circuit for starting the motor, automatic 5 dialling means including a helicoidally advancing drum provided with groups of axially spaced cam discs successively actuating impulsive means for connecting said line in sequence to a plurality of stations, a phonographic device for transmitting 10 an alarm message over said line cam driven clutch means responsive to said motor for causing said

dialling means to select a station, and for thereafter rendering said dialling means inoperative while connecting said phonographic device to said line for transmission of the alarm message, and cam controlled switching means adapted to open 80 the line to release each station subsequent to transmission of the alarm message thereby to permit selection of the succeeding stations.

DISCLAIMER

1,974,551.—*Jean Edouard Tuscher, Petit Ivry, and Marcel Spiro, Paris, France.*
AUTOMATIC TELEPHONE SIGNALING APPARATUS. Patent dated September
25, 1934. Disclaimer filed March 6, 1937, by the assignee, *Signaphone*
Corporation of America.

Hereby enters this disclaimer to claim 12 of said Letters Patent.

[*Official Gazette April 20, 1937.*]
